UNITED STATES PATENT OFFICE.

JAMES HENRY SHAULL, OF CHARLOTTE, MICHIGAN.

AUTOMOBILE STARTING MECHANISM.

1,132,802.

Specification of Letters Patent. Patented Mar. 23, 1915.

Application filed March 24, 1914. Serial No. 826,935.

To all whom it may concern:

Be it known that I, JAMES H. SHAULL, residing at Charlotte, in the county of Eaton and State of Michigan, have invented a new and Improved Automobile Starting Mechanism, of which the following is a specification.

My invention, which relates generally to means for automatically starting automobile engines, is more particularly directed to improvements in that class of motor starters in which the operation of imparting the rotary motion to the engine shaft is effected by means of a reciprocatable rack member.

Primarily my invention has for its object to provide a starting mechanism of the general type mentioned, of a simple, compact, and inexpensive construction, and in which the operation of applying the starting mechanism is under convenient control of the occupant of the motor vehicle.

Furthermore, my invention has for its purpose to provide pneumatically actuated starting mechanism that includes a special construction and arrangement of controlling valves, all of which are arranged for being shifted to the open position by a single lever device and in which the co-operative lever and valve connections are such that the shifting of the said lever operates to open some of the valves as the other valves are automatically shifted to a closed position.

My invention, embodies an improved construction and novel arrangement of parts, including a cylinder or barrel that extends transversely over the engine shaft, a rack reciprocably mounted within the cylinder and having a piston head at its end and having its rack face adapted for meshing with a gear on the engine shaft, a compressed air reservoir mounted upon the vehicle and air leads from the said tank to the opposite ends of the rack holding cylinder and controlling valve devices for alternately changing air under pressure into the opposite ends of the said cylinder.

In its more subordinate features my invention consists in certain details of construction and novel combination of parts, all of which will be hereinafter fully described, specifically pointed out in the appended claims and illustrated in the accompanying drawings, in which:

Figure 1 is a perspective view of a portion of a motor vehicle, the motor engine and my improved starting mechanism operatively

connected therewith. Fig. 2 is a longitudinal section of the transversely located cylinder showing the fluid impelled piston at its normal position. Fig. 3 is a detail sectional view of the air controlling valve devices, the various ones being at a normal or inoperative position. Fig. 4 is a face view of the pinion on the outer end of the motor shaft which co-acts with the piston rack shown in Fig. 2. Fig. 5 is a diagrammatic vertical section of the several air controlling valve devices and the single actuating lever that co-acts therewith, the said valve devices being shown in position for leading the air under high pressure into one end of the cylinder having the reciprocatable rack. Fig. 6 is a similar view of the valve devices, shown as shifted for leading the air under a low pressure into the other end of the said rack contained cylinder.

In carrying out my invention, I provide a cylinder or barrel 1, that extends entirely across the chassis of the motor vehicle, above, but in close proximity to the engine shaft 2, the ends being secured upon the said chassis as shown. The cylinder 1 has an elongated slot 10 in its bottom and through the said slot extends the upper end of a cog gear 3 mounted on the engine shaft 2 and connected therewith by a pawl and ratchet device.

4 designates a rack member that is reciprocably held within the cylinder 1 and which meshes with the gear 3 on the engine shaft 90 as shown, and at the opposite ends the rack member has attached piston heads 5—5 as best shown in Fig. 2, by reference to which it will be observed the cylinder 1 also has air passages 6 and 7 at the opposite ends and an exhaust port 8 near the center thereof.

9 designates a tank or reservoir that is suitably mounted on the vehicle frame from which the air is led to the cylinder 1 for shifting the rack member 4 in the following manner. A pipe 90 leads from the tank 9 to a valve chamber 11 in which is located a valve 12 that is normally held closed by a spring 13 and whose stem 14 projects up through the top of the chamber 11, the latter having an escape port 15 above the valve 12 that discharges into a chamber 16 in direct connection with the air passage 6, in the cylinder 1, through a pipe 17 and which is also in communication, through a pipe 18 and a check valve 19 with a reserve air tank or reservoir 20. Chamber 16 has an outlet

21 surrounded by a valve seat for seating a valve 22 that is closed by a spring and the air pressure from the tank 9 to the cylinder 1 and which has a long stem 23 that passes 5 through the chamber 24 and extends through the end thereof. Chamber 24 has an exhausting port 25 presently again referred to. 26 designates a third chamber provided with an air inlet 27 having a valve seat to accommodate 10 a valve 28 held closed by the spring 28^a and whose stem 29 projects beyond the said chamber 26. The air inlet 27 of the chamber 26 connects with a pipe 30 that joins with the reserve air tank 20 and the 15 said chamber 26 has an air outlet 32, from which, through the pipe 33 the air is led to a supplemental air tank 34 joined by the pipe 35 in the air inlet 7 in the main cylinder 1.

20 It should be stated that the main air tank or reservoir and the valve devices that control the flow of the air to the opposite ends of the racks holding cylinder 1 may be mounted upon the vehicle chassis or framing 25 to suit the particular character of machine to which my starting mechanism is to be applied, but in every instance the valve devices are relatively so arranged and combined that the stems of the said three controlling 30 valves project in like direction and are held in such alinement whereby they are adapted for being engaged by a single controlling rock lever 36 which in the drawings is shown so pivoted at 37, that when one end 35 thereof is projected to engage with the stem of the valve 14 the other end is free of engagement with stems 23 and 29 of the two other valves, such arrangement of parts being provided so that when the lever 36 is 40 rocked to the position shown in Fig. 5, the valve 12 will be forced down to the open position to let the air from the main tank pass to the rack carrying cylinder, adjacent the rack to thereby force the piston rack 45 forwardly in the cylinder or barrel 1, causing the gear, on the engine shaft to be rotated, and to thereby spin the motor, it being understood that the gear on the engine shaft connects with the shaft by a ratchet 50 and pawl mechanism, see Fig. 4. It will be readily understood from the drawing, when the lever 36 is rocked to the position stated, its other end lifts from the stems of the two other valves which are now held closed by 55 their co-acting springs and the air pressure that passes from the main tank to the cylinder 1. When the rack member is at the end of its forwardly forced stroke, the atmospheric pressure in the barrel or cylinder 1 60 is compressed into the supplemental tank 34 which allows the piston rack to reach its extreme forward limit. After the action just explained is completed, the operator in the motor vehicle, through the actuating rod 38, 65 swings the lever 36 in the opposite direction

and the said air in the tank 34 is held therein under compression until the valve devices are shifted for returning the piston rack to its first position which is done in the manner to be here presently explained, see Fig. 6, 70 which now causes the valve 12 to shift and close off the air from the main air tank; and at the same time it opens the other two valves and permits the air from the reserve tank 20 to flow out to the supplemental tank 75 34 having air under compression, from which the air now discharges against the rack piston, causing such piston to return to its first position. During this latter operation, the air in back of the piston exhausts 80 through the port 6, through the pipe 17 into the chamber 16 through the now open port 22 into the chamber 24 and to atmosphere through the port 25. As the rack piston moves back to the first position to uncover 85 the exhaust port 8, the air reserve pressure is instantly reduced and the rack piston is held from being joined against the end of the barrel, it being understood the valve devices in the system are now under a normal 90 position and are not to be changed until it is again desired to start the motor shaft, when all that is required is to shift the lever to open the valve 12. It should be mentioned that since but little power is required 95 for returning the piston rack member to its first position, as the turning gear on the engine shaft runs loose on the return movement of the said rack member, the pressure held up in the reserve tank 20 and the tank 100 34 mounted on one end of the barrel 1 is always sufficient to effect the said return movement of the piston rack. The importance of providing for the high and low air pressure for actuating the piston rack is 105 apparent when it is considered that a considerable impelling force on the piston rack is necessary to cause it, through the gear engine shaft to spin the engine and only enough pressure being necessary to sufficiently return the rack back to its first position. 110

By reason of arranging the valve devices as shown the necessity of manually controlling the pressure from the main tank for moving the piston rack back is entirely avoided since the air pressure automatically adjusts itself to bring it down to the low pressure needed for returning the said rack, the operator in the car is only required to 115 shift a single lever the latter being rocked one way for applying the high pressure air for spinning the motor shaft and tiller in another direction to permit the now supplemental or low pressure air contained within the piping system outside of the main compression tank for shifting the rack piston back. The operation of spinning the engine shaft may be repeated as desired by 120 the operator in the car by simply moving 125 130

the rod that joins with the valve shifting lever, which rod in practice may be joined with a hand control adjacent the sleeving column of the machine as shown.

5 From the foregoing description, taken in connection with the accompanying drawings, the complete construction, the manner in which my starting mechanism is operated and the advantages thereof, will be 10 readily apparent.

The arrangement and coöperative connection of the several parts that constitute my complete mechanism are such, that the said mechanism may be readily applied upon any 15 of the well known types of motor vehicles. The entire mechanism is under control of the driver of the machine, who through the shifting of a single lever device applies the power for actuating the mechanism for 20 spinning the motor shaft and simultaneously stores up sufficient reserve energy from the initial energy that passes from the main air tank, for spinning the shaft, for returning the rack member and impelling gear, when 25 the control lever is shifted to change the position of the valve devices in the air distributing system.

What I claim is:—

1. In a starting mechanism; a shaft, a 30 gear on the shaft, means for engaging the said gear and shaft to turn the said gear and shaft together in one direction and to release the shaft when turning the gear in the opposite direction, said means including a cylinder, a piston in the said cylinder and a rack connection between the said piston and the gear; a main air reservoir, a reserve air reservoir, pipe connections between the two reservoirs and the cylinder, a normally 35 closed valve for governing the air passage from the main reservoir to the reserve reservoir and to the cylinder, the said valve when opened adapted to allow air to pass from the main reservoir to the reserve reservoir and to the cylinder to impel the piston therein under a high pressure and to simultaneously supply the reserve reservoir with air, a valve in the said connection between the said reserve reservoir and the cylinder for 40 governing the passage of air from the said reserve reservoir to the said cylinder to impel the said piston on its return stroke, the said cylinder having an exhaust port.

2. In a starting mechanism, a shaft, a gear 45 on the shaft, means for engaging the said gear and shaft to turn the said gear and shaft together in one direction and to release the shaft when turning the gear in the opposite direction, said means including a cylinder, a piston in the said cylinder and a rack connection between the said piston and the gear, a main air reservoir, a reserve air reservoir, pipe connections between the two reservoirs and the cylinder, a normally 50 closed valve for governing the air passage

from the main reservoir to the reserve reservoir and to the said cylinder, the said valve when opened adapted to allow air to pass from the main reservoir to the reserve reservoir and to the cylinder to impel the piston 70 therein under a high pressure and to simultaneously supply the reserve reservoir with air, a valve in the said connection between the said reserve reservoir and the said cylinder for governing the passage of air from 75 the said reserve reservoir to the said cylinder to impel the said piston on its return stroke, the said cylinder having an exhaust port, and means for normally holding the air pressure in the said reserve reservoir. 80

3. In a starting mechanism, the combination with a shaft, a gear mounted thereon and ratchet and pawl devices that connect the gear and the shaft, a cylinder, a piston within the cylinder having a rack portion 85 that meshes with the shaft gear and is adapted, under a forward movement, to impel the gear with the shaft and under a reverse movement to turn the gear loosely upon the shaft, a compressed air supply, a 90 pipe connection that joins the said supply with one end of the cylinder, a reserve air reservoir in communication with one end of the cylinder and with the aforesaid pipe connection, a controlling valve that normally cuts out the air supply from the piston cylinder and the reserve air reservoir, a controlling valve mechanism operable under one adjustment for opening up communication with one end of the piston cylinder to 95 lead a high air pressure against the piston to impel it to cause it to spin the shaft and simultaneously lead a portion of the said high air pressure into the reserve air reservoir, the said valve mechanism under another adjustment being adjusted to exhaust air from the front of the piston that impelled it forwardly and simultaneously open up communication between the reserve or low air pressure reservoir and the piston 100 cylinder to impel the piston back and to turn the gear loosely upon the shaft. 105

4. In a starting means for motor engines, the combination with the engine shaft and a gear thereon having a ratchet and pawl connection therewith, of a cylinder that extends transversely over the said shaft and has a slot through which the gear projects, a piston within the cylinder having a rack that meshes with the gear, a source of compressed air supply, an air distributing system that connects the said source of an air supply with the opposite ends of the cylinder, said system including valve devices and means for storing up a reserve low air pressure when the air supply is opened, means under control of the operator for first shifting the valve devices for opening up the air supply direct to the cylinder for feeding air under high pressure against the rack piston 110 115 120 125 130 135

to shift it for moving the engine shaft, and simultaneously storing up the reserve low air pressure, for then shifting the said valve devices for cutting out the main air tank 5 and opening up the low air pressure to the cylinder for returning the piston rack to the first or normal position.

5. In an engine starter, the combination with the starting motor, which includes a 10 cylinder, a free piston in the cylinder, an operative connection between the said piston and the shaft of the engine to be started; of an air reservoir, means including a control valve for effecting the communication between the said reservoir and the said cylinder to move the said piston on its starting stroke, means for simultaneously storing up the air contents of the said cylinder on the other side of the said piston under a low 20 pressure to return to the said piston when the pressure from the said reservoir is cut off and other means for exhausting the first mentioned air charge from the cylinder to permit the return of the piston.
- 25 6. In an engine starter, the combination with the starting motor, which includes a cylinder, a free piston in the cylinder, an operative connection between the said piston and the shaft of the apparatus to be started; 30 of an air reservoir, means including a control valve for effecting the communication between the said reservoir and the said cylinder to move the said piston on its starting stroke, means for simultaneously storing up 35 the air contents of the said cylinder on the other side of the said piston under a low

pressure to return to the said piston when the pressure from the said reservoir is cut off and other means for exhausting the first mentioned air charge from the cylinder to 40 permit the return of the piston, a reserve reservoir and means controlled by the said first mentioned valve for receiving a portion of the initial charge from the first mentioned reservoir and a control valve for admitting the air from the said reserve reservoir into said cylinder to augment the piston returning charge.

7. In a starting mechanism, the combination with a shaft, a gear thereon, a ratchet and pawl connection that connects the gear and the shaft, a starting motor that comprises a cylinder, a free piston within the cylinder, an operative connection between the piston and the gear on the shaft; of an air reservoir, means for delivering air from the said reservoir under full pressure directly against one end of the aforesaid piston to impel the said piston to spin the shaft, means for storing up a portion of the 60 said delivered air, other means for subsequently delivering the said stored up portion of air against the other end of the said piston to restore the said piston, and further means for exhausting the high pressure air 65 from the said cylinder during the return stroke of the piston.
